FIG. 6

INVENTOR
ALBERT H. NELSON
BY *Ellis Spear Jr.*
ATTY.

UNITED STATES PATENT OFFICE.

ALBERT H. NELSON, OF NEWTON, MASSACHUSETTS, ASSIGNOR, BY MESNE ASSIGNMENTS, OF ONE-THIRD TO JOHN R. LEARNED, OF NEWTON, MASSACHUSETTS, ONE-THIRD TO CLIFFORD J. LARKIN, OF EVERETT, MASSACHUSETTS, AND ONE-THIRD TO LELIAND COBURN NELSON, OF FANEUIL, MASSACHUSETTS.

LIGHTER.

1,026,695.

Specification of Letters Patent.

Patented May 21, 1912.

Application filed November 12, 1910. Serial No. 591,933.

To all whom it may concern:

Be it known that I, ALBERT H. NELSON, a citizen of the United States, residing at Newton, county of Middlesex, Commonwealth of Massachusetts, have invented certain new and useful Improvements in Lighters, of which the following is a specification.

This invention relates to sparking devices, and particularly to a spark-igniter for lighting gas jets or similar burners. In devices of this sort it is very desirable that the parts which are to deliver the spark be normally positioned away from the flame. In those types of lighters in which sparks are generated by friction between two bodies, it is furthermore of prime importance that the motion of the parts be so arranged as to deliver the spark at the proper point and, at the same time, that the relative movement of the parts during actuation be sufficiently rapid to emit the spark desired. To the end, therefore, of providing means for securing the various features of advantage above suggested, I have devised my present invention.

25 This I will more fully describe in the specification which follows, reference being had to the drawings which form a part thereof and in these drawings I have shown as an illustrative embodiment of the invention itself, a device which I find well adapted to practical use.

Throughout specification and drawings like reference numerals are employed to indicate corresponding parts and in the drawings:—Figure 1 is a side view of my igniter in normal position, Fig. 2 is a view of the same from the opposite side, Fig. 3 is a view of the device in position to deliver the spark, Fig. 4 is a view showing a position of the parts after the spark is delivered, Fig. 5 is an end view of the device positioned as in Fig. 3, and Fig. 6 is a view of the containing plug.

Upon any suitable fastening device, such as the clamp 1, which is adapted to embrace the gas tip, indicated in dotted lines as 2, is mounted a bearing 3 on which is provided a projecting arm 4 fitted with an inwardly

projecting pin 5. Within the bearing 3 is pivoted an arm 6 having a laterally projecting ear 7. On the opposite end of the lever 6 is formed a threaded socket 8 into which a screw plug 9 is adjusted. The screw plug 9 is externally threaded and preferably provided with a milling head and is internally bored or recessed to receive a spring 10 which is adapted to yieldingly press down the pencil 11. Below the socket 8 extends an arm 12 to which is pivoted at 13 a sparking lever 14 which carries on its outer end 15 a roughened segment 16 which is concentric with the pivot 13 so that it will travel in its rotation past the lower end of the plug 9 in contact with the pencil 11.

The inner end of the lever 14 normally lies below the pin 5 which is set in the path traveled by that end when the lever 6 is operated. A spring 17, hooked at one end in the ear 7 and at the other to the upper end of the bearing 3, tends normally to keep the 65 sparking end of the lever depressed. A chain 18 is provided for drawing down the rear end of the lever to raise the spark end. The spring 19 is also hooked in the ear 7, but, at its opposite end engages the rear end 75 of the lever 14, thus tending to hold the roughened segment 16 rotated past the plug 9.

The operation of my device is as follows: The parts normally stand in the position shown in Fig. 1. When it is desired to operate the device the chain 18 is pulled, raising the sparking end of the lever 6 until it comes into the position shown in Fig. 3. In this position the sparking end of the lever is 80 swung up through substantially 90°, so that it stands in a nearly vertical position and at about the height of the tip of the gas jet. During this general movement of the sparking end of the lever the segment 16 has undergone a rearward movement due to the arrest of the inner end of the lever 14 by the pin 5. This arrest of the inner end of the lever 14, owing to the change in position of the main lever 6 with regard to the 85 projection 4, rotates the segment 16 backward.

slowly until at the time that the parts reach the position shown in Fig. 3 it is withdrawn or backed up through the very angle which its segment measures. In passing from the position shown in Fig. 3 to that shown in Fig. 4, the lever 6 has moved sufficiently far to the vertical to clear the inner end of the lever 14 of the pin 5. As soon as the inner end of the lever is free from its pin, its spring 19 quickly draws it straight, giving the roughened segment 16 a rapid rotation past the end of the plug 19, tearing from the end of the pencil 11 a shower of sparks which are projected into the path of the escaping gas as delivered by the gas jet. Upon the release of the chain 18 the spring 17 will return the main lever 6 to position shown in Fig. 1, during which return the inner end of the lever 14 rides over the pin 5, being permitted to make a slightly backward movement on account of the position of the spring 19, but, being immediately drawn back into alinement by that spring as soon as the pin 5 is passed. Thus it will be seen that the parts are normally safely positioned out of the way of the flame, but, by a single motion of the hand of the user, they can be brought into operative position where they will operate as to the frictional parts by the instant automatic relations of the operating spring.

Various modifications in the construction and operation of the device may be made, all without departing from the spirit of my invention if within the limits of the appended claims.

What I, therefore, claim and desire to secure by Letters Patent is:—

1. In an ignition device, a support, a lever pivoted to said support, a second lever pivoted on said first named lever, means for normally holding said second named lever in predetermined position relative to said first named lever, a curved abrasive member and means for supporting a spark producing material, said member and means being mounted one on one lever and the other on the other lever, and means for effecting a relative movement of said levers upon the actuation of the first named lever to secure a passing contact between said abrasive member and said spark producing material.

2. In an ignition device, a support, a lever pivoted to said support, a second lever pivoted on said first named lever, means for normally holding said second named lever in predetermined position relative to said first named lever, a segmental abrasive surface on said second lever and concentric with its point of pivot, means on said first named lever for supporting a spark producing material in yielding contact with said abrasive surface and means for effecting a relative movement of two said levers upon the actuation of the first named lever.

3. In an ignition device, a support, a lever pivoted to said support, a second lever pivoted on said first named lever and adjacent to one end thereof, resilient means for holding said first named lever in a predetermined position relative to said support, resilient means for holding said second named lever in predetermined position relative to said first named lever, a segmental abrasive surface on said second lever and concentric with its point of pivot, means on said first named lever for supporting a spark producing material in yielding contact with said abrasive surface and means for effecting a relative movement of said two levers upon the actuation of the first named lever.

4. In a gas lighter, a clamp for a gas jet, a lever pivoted to said clamp, an ignition lever pivoted to said first named lever near one of its ends, means for yieldingly holding said first named lever with its ignition end depressed, an abrasive segmental surface on said ignition lever concentric with the pivot thereof, means for holding a spark producing material yieldingly against said surface, means for yieldingly holding said two levers so relatively positioned that said abrasive segment shall be turned past said spark producing material and means for retarding the opposite end of said ignition lever during the swing of said first named lever.

5. In a gas lighter, a clamp for a gas jet having a bearing thereon, a lever pivoted within said bearing, an ignition lever pivoted to said first named lever near one of its ends, means for yieldingly holding said first named lever with its ignition end depressed, an abrasive segmental surface on said ignition lever concentric with the pivot thereof, means for holding a spark producing material yieldingly against said surface, means for yieldingly holding said two levers so relatively positioned that said abrasive segment shall be turned past said spark producing material and means for retarding the opposite end of said ignition lever during the swing of said first named lever until the sparking end of said lever shall be adjacent to said gas tip, said retarding means thereupon ceasing to be effective, whereby said friction lever will be released and said friction segment suddenly rotated.

6. In a gas lighter, a clamp for a gas jet having a bearing thereon, a lever pivoted within said bearing, an ignition lever pivoted to said first named lever near one of its ends, means for yieldingly holding said first named lever with its ignition end depressed, an abrasive segmental surface on said ignition lever concentric with the pivot thereof, means for holding a spark producing material yieldingly against said surface, a spring connecting the inner end of said second named lever for holding said two levers.

vers so alined that said abrasive segment shall be turned past said spark producing material and means for retarding the opposite end of said ignition lever during the swing of said first named lever until the sparking end of said lever shall be adjacent to said gas tip, said retarding means thereupon ceasing to be effective, whereby said friction

lever will be released and said friction segment suddenly rotated. ¹⁰

In testimony whereof, I affix my signature in presence of two witnesses.
